Des. no. 20,239

UNITED STATES PATENT OFFICE.

ADOLPH PETZOLD, OF PHILADELPHIA, PENNSYLVANIA, ASSIGNOR TO JOHN BROMLEY & SONS.

DESIGN FOR A TABLE-COVER, &c.

SPECIFICATION forming part of Design No. 20,239, dated October 28, 1890.

Application filed August 30, 1890. Serial No. 363,556. Term of patent 3½ years.

To all whom it may concern:

Be it known that I, ADOLPH PETZOLD, a citizen of the United States, residing in the city of Philadelphia, State of Pennsylvania, have invented and produced a new and original Design for a Table-Cover and Curtain, of which the following is a full, clear, and exact description, reference being had to the accompanying drawing, forming a part of this specification.

My invention has relation to the surface ornamentation of woven textile fabrics, and is applicable more particularly to the ornamentation of a chenille table-cover and the border of a curtain. It consists, principally, of the ornamental bordering, which comprises its dis-

tinguishing features. The isolated figures of the open field center may therefore be varied or omitted. It is fully illustrated in the accompanying photographic drawing, to which reference is hereby made.

I claim—

The design for the border of a curtain or table-cover, substantially as shown and set forth.

In testimony whereof I have hereunto affixed my signature this 31st day of July, A. D. 1890.

ADOLPH PETZOLD.
